UNITED STATES PATENT OFFICE

2,435,055

STEAM GENERATOR

Gustav A. Rehm, Worcester, Mass., assignor to
 Riley Stoker Corporation, Worcester, Mass., a
 corporation of Massachusetts

Application November 16, 1944; Serial No. 563,653

3 Claims. (Cl. 122—347)

1

This invention relates to steam generators, and more particularly to steam generators of the water tube type having a combustion chamber provided with water-cooled side walls.

One form of steam generator in common use comprises upper and lower longitudinal drums connected by a bank of upright water tubes, a combustion chamber in front of the tube bank, upright water wall tubes associated with the side walls of the combustion chamber and communicating at their upper ends with the upper drum, and longitudinal headers connected to the lower ends of the water wall tubes. In order to complete a path for circulation of water through the water wall tubes, two constructions have been utilized heretofore. In one of these prior constructions the headers have been connected to the lower drum, but since sediment tends to settle in this drum by gravity there is danger of supplying dirty water to the highly heated water wall tubes unless care is taken to operate the boiler blow-down system at proper intervals. In the other of these prior constructions rows of water tubes have extended laterally from opposite sides of the upper drum and thence downwardly along the side walls of the setting to connect with the rear portions of the headers, but if the water level in the upper drum should drop only slightly the supply of water to the headers and water wall tubes would fail entirely. This would result in overheating of the water wall tubes and serious damage thereto.

It is accordingly one object of the invention to avoid these difficulties with prior steam generators of the general type discussed above by providing an improved circulating path for supplying water to the water wall tubes.

It is a further object of the invention to provide an improved steam generator of the type having upper and lower longitudinal drums connected by a bank of upright water tubes and a combustion chamber in front of the tube bank, and particularly to include a water wall system for the combustion chamber which will be reliably supplied with water from the upper drum despite appreciable fluctuations in the boiler water level.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

2

Fig. 1 is a longitudinal section through a steam generator, taken on the line 1—1 of Fig. 2;

Fig. 2 is a section taken on the line 2—2 of Fig. 1;

Fig. 3 is a section taken on the line 3—3 of Fig. 2;

Fig. 4 is a section taken on the line 4—4 of Fig. 2; and

Fig. 5 is a fragmentary detail in plan showing 10 a portion of the water wall header construction.

The embodiment illustrated comprises a setting having a front wall 10, opposed side walls 11, and a rear wall 12. In the rear portion of the setting there is provided a longitudinal upper steam-and-water drum 14, a longitudinal lower water drum 15, and a bank of upright water tubes 16 connecting the drums and arranged in transverse rows to form a convection heating surface. The front portion of the setting encloses a combustion chamber 18 into which fuel and air may be delivered through a suitable burner opening 19 in the front wall 10. Three upright transverse baffles 20 are mounted in the tube bank 16 to direct the hot gases in a tortuous course as they flow 25 rearwardly from the combustion chamber and into contact with the water tubes, the gases finally escaping through outlet ducts 21 at the rear of the setting. The gases make four passes over the water tubes before reaching the outlet ducts. The fourth or rearmost gas pass is employed as an economizer to heat the incoming feed water, and for this purpose an upright partition 23 is mounted within the lower drum 15 directly beneath the rearmost baffle 20. Also, the 30 feed water is delivered to the rear portion of the upper drum 14 and behind a partition 24 therein by means of a pipe 25, this partition joining the lower wall of the drum between two of the transverse rows of tubes in the rear gas pass. Consequently the feed water is compelled to descend 35 through the rearmost tubes to the lower drum 15 and then flow upwardly through the tubes in the front portion of the rear gas pass before entering the main circulating system of the boiler. 40 In the top of the upper drum 14 there is provided a steam discharge nozzle 27 having a steam baffle 28 therebeneath.

The combustion chamber 18 is provided with a water wall system to protect and support the walls, and to generate steam at a relatively high rate. For this purpose a longitudinal lower header 30 extends along the lower portion of each side wall 11, and a longitudinal upper header 31 extends along the top of each side wall. Up- 45 right water wall tubes 32 extend upwardly from

the lower headers 30 and adjacent the side walls 11, the upper portions of these tubes being bent inwardly to cross one another above the center of the combustion chamber 18 and support the roof 34 thereof, the upper ends of the tubes being connected to the upper headers 31. Releaser tubes 35 connect the upper headers with the front end of the upper drum 14, preferably above the normal water level. At the rear of the combustion chamber 18, the two lower headers 30 are connected by a transverse header 37 from which two rows of water tubes 38 extend upwardly to enter the upper drum 14 in circumferential rows. These tubes 38 support a refractory bridge wall 39 which shields the lower drum 15 from the radiant heat of the furnace. The junction between each longitudinal header 30 and the transverse header 37 may be effected by means of a welding T 40, as shown in Fig. 5.

It is of great importance to ensure a continuous and adequate supply of clean water to the lower headers 30 and 37. Even a momentary interruption to such supply may result in overheating of the water tubes 32 and 38, for these tubes are subjected to radiant heat and they generate steam at a very high rate. Accordingly I provide means for supplying these headers directly from the bottom of the upper drum 14, which is less likely to contain suspended insoluble matter than the lower drum. For this purpose some of the boiler water tubes 16 are preferably omitted at the center of the third gas pass to provide a space 42 beneath the upper drum 14, with groups of tubes 16 on opposite sides of this space. Within the space 42 there are provided upright water tubes 43 with their upper ends connected to the bottom of the upper drum 14, close to the vertical axial plane thereof, and their lower portions bent laterally outward to extend between the lower portions of the adjacent tubes 16 and connect with the rear portions of the lower headers 30. The tubes 43 are appreciably larger in diameter than the tubes 16, and the rows of tubes 16 at the sides of the space 42 are spaced apart rather widely to avoid any interference with the laterally extending lower portions of the tubes 43. Since the tubes 43 are remote from the combustion chamber 18 and in a region of comparatively low gas temperature, they serve as very effective downcomers to ensure an adequate supply of water to the headers 30 and 37. This supply will be maintained in spite of wide fluctuations in the water level in the drum 14, and in fact as long as there is any water in this drum, since the downcomer tubes are connected to the bottom of the drum. Consequently a rapid circulation of clean water will be maintained through the water wall tubes 32 and the bridge wall tubes 38 at all times during the operation of the boiler. By providing the free space 42 for the downcomer tubes 43, adequate ligament strength is obtained between the tube holes in the drum 14 and removal of tubes for replacement is facilitated if this should ever become necessary.

Having thus described my invention, what I claim as new and desire to secure by Letters Patent is:

1. A steam generator comprising a longitudinal steam-and-water drum, a longitudinal water drum therebeneath, a bank of upright water tubes connecting the drums and arranged to leave a space free from such tubes in a region located a substantial distance rearwardly from the front

of the tube bank, walls providing a combustion chamber in front of the tube bank, longitudinal headers on opposite sides of the combustion chamber, downcomer tubes located within the

5 said space with their upper ends connected to the bottom of the upper drum close to the vertical axial plane thereof, the lower ends of the downcomer tubes being connected to the rear portions of the headers, and upright water wall tubes adjacent the side walls of the combustion chamber with their lower ends connected to the headers and their upper ends communicating with the steam-and-water drum.

2. A steam generator comprising a longitudinal steam-and-water drum, a longitudinal water drum therebeneath, a bank of upright water tubes connecting the drums and arranged to leave a space free from such tubes in a region located a substantial distance rearwardly from the front

10 of the tube bank, there being groups of said water tubes on opposite sides of the said space, walls providing a combustion chamber in front of the tube bank, longitudinal headers on opposite sides of the combustion chamber, downcomer tubes

25 having upright portions located in the said space and connected at their upper ends to the bottom of the upper drum, the lower portions of the downcomer tubes being bent laterally outward to extend between the tubes of said groups and connect with the rear portions of the headers, and upright water wall tubes adjacent the side walls of the combustion chamber with their lower ends connected to the headers and their upper ends communicating with the steam-and-water drum.

3. A steam generator comprising a longitudinal steam-and-water drum, a longitudinal water drum therebeneath, a bank of upright water tubes connecting the drums and arranged to leave a space free from such tubes in a region located a substantial distance rearwardly from the front of the tube bank, walls providing a combustion chamber in front of the tube bank, longitudinal headers on opposite sides of the combustion chamber, downcomer tubes located within the

40 said space with their upper ends connected to the bottom of the upper drum close to the vertical axial plane thereof, the lower ends of the downcomer tubes being connected to the rear portions of the headers, upright water wall tubes adjacent the side walls of the combustion chamber with their lower ends connected to the headers and their upper ends communicating with the steam-and-water drum.

45 5. A steam generator comprising a longitudinal steam-and-water drum, a longitudinal water drum therebeneath, a bank of upright water tubes connecting the drums and arranged to leave a space free from such tubes in a region located a substantial distance rearwardly from the front of the tube bank, walls providing a combustion chamber in front of the tube bank, longitudinal headers on opposite sides of the combustion chamber, downcomer tubes located within the

50 said space with their upper ends connected to the bottom of the upper drum close to the vertical axial plane thereof, the lower ends of the downcomer tubes being connected to the rear portions of the headers, upright water wall tubes adjacent the side walls of the combustion chamber with their lower ends connected to the headers and their upper ends communicating with the steam-and-water drum.

55 6. A steam generator comprising a longitudinal steam-and-water drum, a longitudinal water drum therebeneath, a bank of upright water tubes connecting the drums and arranged to leave a space free from such tubes in a region located a substantial distance rearwardly from the front of the tube bank, walls providing a combustion chamber in front of the tube bank, longitudinal headers on opposite sides of the combustion chamber, downcomer tubes located within the

60 said space with their upper ends connected to the bottom of the upper drum close to the vertical axial plane thereof, the lower ends of the downcomer tubes being connected to the rear portions of the headers, upright water wall tubes adjacent the side walls of the combustion chamber with their lower ends connected to the headers and their upper ends communicating with the steam-and-water drum.
